Primary Examiner — Amber R Stiles*Assistant Examiner* — Earl B Elowsky(74) *Attorney, Agent, or Firm* — Snell & Wilmer L.L.P.(57) **CLAIM**

The ornamental design for a gate valve clamp as shown and described.

DESCRIPTION

FIG. 1 is a top perspective view of the gate valve clamp, showing our new design;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines in the drawings depict portions of the gate valve clamp that form no part of the claimed design.
